UNITED STATES PATENT OFFICE.

CHARLES ED. HAVILAND, OF LIMOGES, FRANCE.

DESIGN FOR A DISH.

SPECIFICATION forming part of Design No. 20,632, dated March 24, 1891.

Application filed February 24, 1891. Serial No. 382,637. Term of patent 14 years.

To all whom it may concern:

Be it known that I, CHARLES EDWARD HAVILAND, a citizen of the United States, residing at the city of Limoges, in the Republic of France, have invented and produced a new and original Design for a Dish or other Article, of which the following is a specification, reference being had to the accompanying drawings, forming part thereof.

10 Figure 1 is a top plan view of a dish, showing my design; and Figs. 2 and 3 are vertical sections of same on the dotted lines 2 2 and 3 3 of Fig. 1.

15 The leading feature of my design consists in the scalloped outline bordering the edge of the dish and bearing ornamental scrolls partly in relief and partly *in intaglio*.

In the drawings, A designates the dish having an outline composed of the scalloped edges

lettered B and C, the latter being at the corners of the dish and connected by the scalloped edges B. The scalloped edges B are provided with the conventionalized foliate scrolls D in relief, while the scalloped edges C at the corners of the dish are provided with 25 the ornamental scrolls F G H I, the scrolls F G H being in relief and the scrolls I *in intaglio*, as illustrated in the drawings.

What I claim is—

The design for a dish or other article, substantially as shown and described.

Signed at the city of Limoges, in the Republic of France, this 10th day of February, 1891.

CHARLES ED. HAVILAND. [L. S.]
